CLAIM

The ornamental design for a grill, as shown and described.

DESCRIPTION

FIG. 1 is a top plan view of a grill showing my new design;

FIG. 2 is a right side elevational view thereof;

FIG. 3 is a bottom plan view thereof;

FIG. 4 is a left side elevational view thereof;

FIG. 5 is a front elevational view thereof;

FIG. 6 is a rear elevational view thereof; and

FIG. 7 is a cross-sectional view thereof, shown at a reduced scale, taken on line 7—7 of FIG. 1.
